DOHERTY RESEARCH COMPANY, OF NEW YORK, N. Y., A CORPORATION OF DELA-
WARE

FUEL BURNER

Application filed March 29, 1929. Serial No. 350,959.

This invention relates to a fuel burner and more particularly to fuel burners adapted to function under high temperatures and pressures such as occur in connection with internal combustion engines or in other relations where fuel is burned under conditions which adversely affect metallic parts of the burner.

It is among the objects of this invention to provide a fuel burner which shall be of simple, compact construction, durable and efficient in operation and which will have few elements liable to get out of order, and which may be easily taken apart for inspection and conditioning.

It is a further object of this invention to provide for the protection of such metallic parts as are subjected to the high temperature of combustion in and adjacent the fuel burner. To this end, one feature of the invention contemplates the use for the inner elements of the burner of refractory material of such thickness as to fully protect the metallic housing of the burner and the fuel supply line connected therewith.

It is a further object of this invention to provide for complete and efficient combustion of the fuel with the minimum quantity of air essential for its combustion. To this end means are provided whereby the fuel is thoroughly mixed with the air of combustion at the point at which combustion occurs by giving the air a rotating motion over the surface from which the fuel enters.

These and further objects and features of the invention will be seen from the accompanying drawings, in which:—

Fig. 1 is a longitudinal section through the burner, parts being shown in side elevation;

Fig. 2 is a section of the burner along the line 2—2 of Fig. 1;

Fig. 3 is a section of the burner along the line 3—3 of Fig. 1; and

Fig. 4 is an end view of a deflecting member.

Referring particularly to Fig. 1, 10 indicates a housing preferably constructed of a metallic sleeve which is externally screw threaded at each end as indicated at 12 and 14 to accommodate the internally screw threaded flanges 16 and 18.

Within the metallic sleeve 10 is a refractory core 20 which is provided with a central passage 22 extending longitudinally therethrough. The passage 22 has a conical portion 24 adapted to accommodate a cone-shaped deflector 26 having spiral deflecting vanes thereon as indicated at 28. The refractory portion 20 is made of hard, heat-resistant, non-porous material and is preferably formed with a firm union to the metal sleeve 10 by being either baked in place or cemented therein.

Adjacent the refractory member 20 is an annular member 30 also of refractory material but of such different composition from the refractory member 20 as to be permeable or porous although also possessing good heat resisting and non-conducting properties. The member 30 is provided with an annular groove 32 about its external circumference. A pipe 34 is adapted to lead liquid or gaseous fuel to the annular groove 32.

A third refractory element of similar composition to the member 20 is provided as indicated at 36 and is formed with the passage 38 centrally therethrough adapted when in position to register with the small end of a frusto-conical passage 40 in the refractory annulus 30.

In operation, air for combustion is supplied under high pressure at 22. At the small end of the frusto-conical passage 24, it is deflected by the vanes 28 of deflector 26 into helical paths about the surface of the conical passage. From a consideration of Figs. 3 and 4 it will be seen that the helical passages formed by the deflecting vanes 28 are of substantially constant capacity throughout the length of the deflecting member 26 so that the velocity of the air charge entering at the small end of the deflecting member 26 is in no way impaired by alteration in the cross-section of the passage through which the air flows. The air is however given a high rotational velocity and enters the passage 40 through the porous member 30 in such a manner as to traverse a large portion of the surface thereof.

Fuel which may be gaseous or liquid is supplied from the passage 34 to the annular

chamber 32 and passes through the porous refractory 30. Upon contacting with the air circulating about the surface of the passage 40 the fuel is ignited and burns, passing to the combustion chamber of the furnace or engine through the passage 38 in refractory member 36.

The deflector 26 is also preferably constructed of refractory material. It will thus be seen that all metallic parts of the burner are protected by a thick coating of refractory from the high temperature of the combustion taking place within the burner and the conveyor pipe 42, or other chamber immediately adjacent thereto which also has a refractory lining 44.

By the construction shown, the burner may be easily attached or removed from the furnace or combustion chamber and upon removal the element 20 or 36 may be taken out thereby permitting the removal of the porous member 30 for cleaning or to be substituted by new porous member.

Although there is herein described a specific embodiment of the invention, it will be obvious to those skilled in the art that various modifications may be made in the details of construction and in the design and the proportions of the various parts without departing from the invention herein set forth.

Having thus described the invention, what is claimed as new is:

1. In a fuel burner, a casing, a refractory on the interior of said casing forming a heat insulated passage therethrough, means to supply combustion supporting gases at one end of said casing, means to supply fuel centrally of said casing through a portion of said refractory, and means in said passage to give the gases entering the same a rotating motion prior to contact with the fuel.

2. In a fuel burner, a casing, a refractory on the interior of said casing forming a heat insulated passage therethrough, means to supply combustion supporting gases at one end of said casing, means to supply fuel centrally of said casing through a portion of said refractory, and a refractory deflector in said passage to give the gases entering the same a rotating motion prior to contact with the fuel.

3. A fuel burner including a casing, a lining in said casing having a central section of permeable refractory material, outer sections of non-porous refractory material, and means to supply fuel to said burner through said permeable section.

4. A fuel burner including a metallic casing, a lining in said casing formed of two different heat insulating refractories, one of said refractories being impermeable and the other being permeable, and means to supply fuel to said burner through said permeable refractory.

5. A fuel burner including a metallic casing open at each end, a heat insulating refrac-

tory coating on the interior wall of said casing forming a heat insulated passage of varying cross section, means to force a combustion supporting gas through said passage, and means to supply fuel to said gas through said refractory material.

6. A fuel burner having a passage longitudinally therethrough, said passage including two frusto-conical portions with the large ends abutting, means to supply a combustion supporting medium to the small end of one of said frusto-conical portions, and means to supply fuel to the surface of the other of said frusto-conical portions.

7. A fuel burner having a passage longitudinally therethrough, said passage including two frusto-conical portions with the large ends abutting, means to supply a combustion supporting medium to the small end of one of said frusto-conical portions, means to give said combustion supporting medium a rotating motion and means to supply fuel to the surface of other frusto-conical portion.

8. A fuel burner including a member of impervious refractory material having a frusto-conical passage therethrough, a member of permeable refractory material having a frusto-conical passage therethrough, said members being placed so that the large ends of said frusto-conical passages register, means to supply combustion supporting medium to the small end of the frusto-conical passage in said impervious refractory member, and means to supply fuel through the permeable refractory material to the surface of the frusto-conical passage therethrough.

9. A fuel burner including a refractory body of heat insulating material, a portion of which is impermeable and a portion of which is permeable, a passage therethrough, and means to supply fuel to said passage through said permeable portion.

10. A fuel burner including a refractory body of heat insulating material, a portion of which is permeable, a passage therethrough, and means to supply fuel to said passage through said permeable portion and a non-metallic refractory deflecting means in said passage.

11. A fuel burner including a passage through a refractory body of heat insulating material, the ends of said passage being through impermeable refractory and the central portion through permeable refractory.

12. A fuel burner including a passage of gradually increasing cross sectional area, and a deflector therein having helical vanes thereon forming grooves of constant cross sectional area.

13. A fuel burner including a passage of gradually increasing cross sectional area, and deflecting means therein adapted to maintain the effective cross sectional area of the passage constant.

14. In a fuel burner, a casing, a heat in-

sulating refractory on the interior of said casing forming a heat insulated passage therethrough, means to supply combustion supporting gases at one end of said casing, means to supply fuel centrally of said casing, 5 and means in said passage to give the gases entering the same a rotary motion.

In testimony whereof I affix my signature.
WINDER E. GOLDSBOROUGH.
